HARRY E. HARRIS, OF BRIDGEPORT, CONNECTICUT.

TAPPING AND THREADING MACHINE.

1,253,817.

Specification of Letters Patent. Patented Jan. 15, 1918.

Application filed August 19, 1916. Serial No. 115,800.

To all whom it may concern:

Be it known that I, HARRY E. HARRIS, a citizen of the United States, residing at Bridgeport, in the county of Fairfield and 5 State of Connecticut, have invented certain new and useful Improvements in Tapping and Threading Machines, of which the following is a specification.

The invention makes improvements in this 10 class of machines with a view to increasing their facility, accuracy, range, and speed of operation.

One object of the invention is to arrange the parts so that the spindle carrying a tap, 15 die, or other tool for operation on work is rotated automatically in one direction upon the pressing of the work against the tool, and so that the spindle is rotated automatically in the reverse direction to cause the 20 work to run off the tool after the desired action of the tool is completed.

For the purpose of imparting rotary movement to the tool-spindle, a double-cone clutch member is fast on the spindle between two pulleys or other driving elements 25 constituting clutch members mounted independently of the spindle and arranged to have the cone clutch member brought to contact therewith, and it is another object of 30 the invention so to form the parts as to prevent oil or other injurious matter from reaching the friction covering interposed between the coöperating clutch-faces.

It is a further object of the invention to 35 provide a work-holder of such form that the work may be pressed against a tool carried by the spindle by pressure of the operator's chest against the work-holder, leaving his hands free to handle the work, and to provide improved means whereby such a longitudinally-movable holder may be restrained 40 from rotary movement without imposing undue frictional resistance to its longitudinal movement.

Moreover, improved adjustable means are provided whereby the movement of the holder and the work carried thereby toward the tool is limited and stopped exactly at the desired place, so that the work may be 45 tapped or otherwise operated upon precisely to the predetermined depth or length, this being a valuable feature particularly in tapping work to a bottom in a hole that does not go entirely through a piece and also in threading with dies up to a shoulder on the work.

When read in connection with the description herein, the details of construction and arrangement of parts contemplated by the invention will be apparent from the accompanying drawing, forming part hereof, wherein an embodiment of the invention, as adapted to tapping, threading, and performing other work on pieces of material that can be moved to and from working position by hand, is disclosed, for purposes of illustration.

While the disclosures herein now are considered to exemplify a preferable embodiment of the invention, it is to be understood that it is not the intention to be limited necessarily thereto in interpretation of the claims, as it is obvious that alterations and adaptations within the limits of the claims can be made without departing from the nature and spirit of the invention.

Like reference-characters refer to corresponding parts in the views of the drawing, of which—

Figure 1 is a side elevation, certain parts being shown in section;

Fig. 2 is a vertical sectional view through a portion of the work-holder; and

Fig. 3 is a vertical sectional view through the spindle and a portion of its bed.

Having more particular reference to the drawing, 4 designates a base or pedestal forming the support of the machine, and to its top there is secured by suitable fastenings 5 a bed 6. A pan 7, to catch matter removed from the material acted on by the machine and to catch oil, surrounds the bed at or near the top of the base or pedestal.

A spindle-mount is secured at or near one end of the bed 6 by suitable fastenings 8, and this mount includes upright standards 9 oppositely disposed in a line longitudinal of the bed. Each of the standards carries at or near its upper end a journal-box 10. The boxes are alined, each projects from its standard toward the other, and it has at its free end an annular shoulder 11 and an enlarged recess 12 surrounded by the shoulder.

A tool-spindle 13 is journaled and axially movable in the boxes, and at each end it projects beyond a standard 9. The spindle has thereon a clutch-spider or other suitable clutch member that includes a hub 14 accommodated by the recesses 12 of the boxes and held against rotary and axial movement with respect to the spindle by a key 15 and set-screws 16. Spokes 17 radiate from the hub

to a central ring 18. A rim 19 projects from each side of the ring, and the outer annular faces of the rim incline outwardly toward the axis in opposite directions. The rim is formed with circumferential grooves 20 in its outer face, and its outer edges are turned outwardly in a radial direction as annular flanges 21. The outer grooved faces of the rim are covered with leather or suitable comparatively soft friction material 22, which is retained against creeping in an axial direction by adherence to the rim and by the ring 18 and the flanges 21. The grooved and covered rim affords clutch-faces that have a cushioning and easy grip with coacting clutch-faces hereinafter described. The clutch-faces being on the outside of the rim, there is no liability of oil reaching the covering thereof either under the influence of gravity or centrifugal action, and, moreover, the flanges 21 also prevent access of oil to the covering. Thus the frictional characteristics of the covering are not injured by oil. The spindle 13 is made as small as is consistent with the strength required for the uses to which the machine is put, and the clutch member is formed of aluminum or other comparatively light material, so that it is easy to overcome the inertia of the mass in starting, stopping, and reversing the direction of rotation of the spindle.

A clutch member, herein designated as an outside clutch member to distinguish it from the one already described, is positioned on each side of the latter clutch member, which for purposes of distinction is designated as the intermediate clutch member. Each outside clutch member has a hub 23 journaled on the outside of the projecting portion of one of the boxes 10 between the shoulder 11 thereof and a standard 9, the shoulder and standard preventing axial movement of the member. Each member has spokes 24 radiating from its hub to a rim 25, which overlaps one of the clutch-faces of the intermediate clutch member and has on the inside a clutch-face 26 inclined parallel or approximately parallel to that of the intermediate clutch member. The two outside clutch members are mounted coaxially of the tool-spindle and of the intermediate clutch member carried thereby, and they are rotated, when the machine is in operation, in opposite directions by any suitable means, as by belts (not shown) on the outer peripheries of the rim 25 between guard-flanges 27 thereof. The relative arrangement of the parts is such that, when the intermediate clutch member is in the median position between the outside clutch members, its clutch-faces are out of engagement with either of the outside members, and the tool-spindle is at rest. When the spindle is moved axially in one direction, one of the clutch-faces of its clutch member contacts with the clutch-face of one of

the outside clutch members, and the spindle is driven in one direction; and, when the spindle is moved axially in the opposite direction, the contacting clutch-faces will become disengaged, and, the spindle passing the median position, the other pair of clutch-faces will become engaged and the spindle will be rotated in the reverse direction. The ring 18 of the intermediate clutch member extends outwardly between the edges of the rims 25 of the outside clutch members. Below the ring there is a brake-shoe 28, carried by an arm 29 extending through the side of the bed 6 and upwardly through the top of the bed. The arm 29 is pivoted on a bracket 30 on the side of the bed, and its outer portion constitutes a handle 31. The weight of the shoe and the portion of the arm on that side of the pivot is sufficient to keep the shoe normally out of contact with the ring. However, if at any time it is desired to arrest rotation of the tool-spindle in the median position between the outside clutch members, that may be done by pressing the shoe against the ring, but under ordinary conditions of use it is not necessary to employ the hand-brake.

The tool-spindle has on one of its projecting ends a chuck or other suitable holder 32 arranged to hold taps, dies, or other tools, and the chuck is opposed to a work-holder. A work-holder mount 33 is carried by and longitudinally adjustable on the bed 6, and it is held in adjusted position thereon by suitable fastenings 34. The mount 33 includes upright standards 35 oppositely disposed in a line longitudinal of the bed, and aligned guideways 36 at or near the tops of the standards carry a longitudinally-movable work-holder shaft 37 in alignment with the tool-spindle. The shaft at its end opposite to the chuck 32 has any suitable means, such as a socket 38, for retaining a work-holder for material being worked by the tool held in the chuck; and on its other end the shaft is formed with a breast plate or pad 39, arranged to be pressed against by the body of the operator to move the holder and material held thereby toward the tool in the chuck.

In order to keep the work-holder shaft and work held thereby from turning while the work is being acted upon by a tool in the chuck, the shaft is enveloped between the standards 35 by a split collar 40 clamped in place by a screw 41 in projecting ears 42, a key 43 being splined into the shaft and collar as insurance against relative rotary movement of the parts, and an arm 44 depends from the collar and has on its lower end an anti-friction roller 45 movable in a guideway 46 fixed to the amount 33. The guideway prevents swinging movement of the arm and thereby rotary movement of the shaft. This arrangement, including the

anti-friction roller, offers comparatively little resistance to the advancement and retraction of the work-holder shaft, even when the turning tendency is great. Therefore, no 5 such frictional resistance occurs as will keep the work from leading uniformly onto the tool.

A projection 47 extends laterally from the collar 40, and it carries a stop-screw 48 10 in a position parallel to the work-holder shaft, the screw being locked in positions of adjustment by a lock-nut 49. The standard 35 adjacent to the work end of the work-holder shaft has a projection 50 extending 15 therefrom opposite to an end of the stop-screw 48. On contact of the end of the screw with this projection, the movement of the work carried by the shaft toward the tool in the chuck is stopped exactly at the 20 predetermined place. The collar 40 is adjusted to the approximate position required to stop movement of the work toward the tool by movement longitudinally of the shaft upon loosening the clamping-screw 25 41; and, upon again tightening this screw, fine adjustment to the exact point of stopping demanded for the work is made by turning the stop-screw 48.

In the operation of the machine, material 30 to be worked is put in a work-holder on the end of the work-holder shaft opposite to the chuck, the operator bears his chest or other part of his body against the breast plate or pad 39, and he thereby advances the work 35 up against the tap, die, or other tool held in the chuck. The pressure of the work against the tool moves the tool-spindle axially until a clutch-face of the intermediate clutch member engages the clutch-face 26 of the 40 clutch member farther away from the chuck, this latter clutch member being driven in the direction required for operation of the tool in the chuck on the material, and the tool-spindle thereupon is rotated. The tool 45 is advanced into the material until the stop-screw 48 contacts with the projection 50, by which further advance is prevented. The tool having a tendency to follow or draw into the work, the result is that the clutch- 50 faces that have been engaged become disengaged and the operator by means of a hand on the work pulls it toward himself and thereby causes engagement of the other pair of clutch-faces, whereupon reverse rotation 55 is given the tool and the work backed off therefrom. As soon as the tool is backed off the work, the operator removes the work with his left hand and with his right hand replaces it with a new piece and repeats the 60 working operation. If the tool happens to be continuing to rotate in the reverse direction at a time a new piece of material is brought thereagainst, that is immaterial, for pressure of the material against the tool 65 will cause the axial movement of the tool-

spindle necessary for disengagement of the then engaging clutch-faces and the engagement of the pair operating to drive the spindle in the working direction.

Ordinarily drawing action of the tool in 70 the material and the pull of the operator on the work at the end of the operation of the tool on the material, as just described, are sufficient to disengage the clutch-faces driving the tool in the working direction. 75 However, for use in case the parts may become hung for any reason, I provide positive means for disengaging those faces. This means includes a foot-pedal 51 pivoted to the lower portion of the base or 80 pedestal 4 and connected by a link 52 with a lever 53, which lever is connected by a link 54 to one end of an intermediately pivoted lever 55 having its other end forked and carrying trunnions 56 of a collar 57 loose in 85 a grooved sleeve 58 fast on the end of the tool-spindle opposite to the chuck. It will be seen that, by pressing downwardly on the foot-pedal, the tool-spindle, through the instrumentalities just described, will be 90 moved axially in a direction to release the clutch-faces driving the spindle in the working direction. A spring 59 associated with the clutch-releasing means, as by connection at one end to the bed 6 and at the other end 95 to the lever 53, is so tensioned that it has a tendency to maintain the intermediate clutch member normally in a median position between the outside clutch members and in a state of rest. 100

Having thus described my invention, what I claim as new, and desire to secure by Letters Patent is,

1. In a machine of the class described, two coöperable clutch members, one of which has an inclined face for engagement with the other member formed with grooves and covered with comparatively soft friction material. 105

2. In a machine of the class described, two coöperable clutch members, one of which has an inclined clutch-face for engagement with the other member, an outturned annular flange at the edge of said face, and a covering of friction material on said face. 110

3. In a machine of the class described, two coöperable clutch members, one of which comprises a ring, a rim having at one side of said ring an inclined clutch-face for engagement with the other member, an outturned annular flange at the edge of said rim, and a covering of friction material on said clutch-face between said flange and said ring. 120

4. In a machine of the class described, the combination of a rotatable spindle susceptive of axial movement, a clutch member fast on said spindle and having a ring and an inclined clutch-face extending laterally from the ring, a drive clutch member rotatably 125

- mounted independently of said spindle and having a clutch-face coöperable with that of said other clutch member, and a brake-shoe movable to contact with said ring.
5. In a machine of the class described, the combination of suitably supported alined bearing-boxes, a spindle journaled in and having end portions extending beyond said boxes and susceptive of axial movement therein, a lever in engagement with said spindle and arranged to impart axial movement thereto, means whereby said lever is swung, two clutch members rotatably mounted independently of said spindle and susceptive of being driven in opposite directions, a clutch member fast on said spindle between said other clutch members and coöperable with either of them upon axial movement of said spindle, and a spring associated 20 with said lever whereby said spindle clutch member normally is maintained in approximately the median position between said other clutch members.
6. In a machine of the class described, the combination of suitably supported alined bearing-boxes, a tool-spindle journaled in and having end portions extending beyond said boxes and susceptive of axial movement therein, a tool-holder on one end of said spindle, a lever in engagement with the other end portion of said spindle and arranged to impart axial movement thereto, means whereby said lever is swung, two clutch members rotatably mounted independently 35 of said spindle and susceptive of being driven in opposite directions, a clutch member fast on said spindle between said other clutch members and coöperable with either of them upon axial movement of said spindle, and spring associated with said lever whereby said spindle clutch member normally is maintained in the median position between said other clutch members.
7. In a machine of the class described, the combination of a rotatably-mounted tool-spindle susceptive of axial movement under the influence of work, two clutch members rotatably mounted independently of said spindle and susceptive of being driven in opposite
- directions, a clutch member fast on said spindle between said other clutch members and coöperable with either of them upon axial movement of said spindle, a tool-holder at one end of said spindle, a work-holder mount including upright standards having alined guideways, a work-holder shaft longitudinally movable in said guideways in alinement with said tool-spindle, a collar longitudinally movable on said shaft, means whereby said collar is held fixed to said shaft, an arm extending from said collar, a guideway in which the free end of said arm is movable, an adjustable stop-screw on said collar, and a projection on one of said standards and contactable by said stop-screw whereby movement of said shaft toward said tool-holder is limited.
8. In a machine of the class described, a work-holder mount including upright standards having alined guideways, a work-holder shaft longitudinally movable in said guideways, a collar longitudinally movable on said shaft, means whereby said collar is held in fixed position on said shaft, an arm extending from said collar, a guideway in which the free end of said arm is movable, an adjustable stop-screw on said collar, and a projection on one of said standards and contactable by said stop-screw whereby movement of said shaft in one direction is limited.
9. In a machine of the class described, a work-holder mount including upright standards having alined guideways, a work-holder shaft longitudinally movable in said guideways, a collar longitudinally movable on said shaft, means whereby said collar is held in fixed position on said shaft, an arm extending from said collar, an anti-friction member on the free end of said arm, a guideway in which said member traverses, an adjustable stop-screw on said collar, and a projection on one of said standards and contactable by said stop-screw whereby movement of said shaft in one direction is limited.

In witness whereof, I affix my signature.

HARRY E. HARRIS.
